Ats. Attorney

UNITED STATES PATENT OFFICE.

JESÚS CASUSO, OF MANILA, PHILIPPINE ISLANDS, ASSIGNOR OF ONE-FOURTH TO
FERDINAND RUSTANT, OF MANILA, PHILIPPINE ISLANDS.

NON-REFILLABLE BOTTLE.

1,261,212.

Specification of Letters Patent.

Patented Apr. 2, 1918.

Application filed March 6, 1917. Serial No. 152,680.

To all whom it may concern:

Be it known that I, JESÚS CASUSO, a citizen of the United States, residing at Manila, Philippine Islands, have invented certain new and useful Improvements in Non-Refillable Bottles, of which the following is a specification, reference being had therein to the accompanying drawings.

This invention relates to a non-refillable bottle and has for its principal object the production of a structure which is adapted to permit the contents of the bottle to be easily emptied therefrom although positively preventing the refilling of the bottle.

Another object of this invention is the production of a non-refillable bottle wherein after the bottle has once been filled a hood is positioned within the neck, which hood is adapted to contain a ball for preventing the refilling of the bottle although when the bottle is inverted the ball will remove from its seat and permit the emptying of the contents from the bottle.

A still further object of this invention is the production of a non-refillable bottle wherein a plurality of tubes are carried by the hood so as to extend from its sides and overhang its top portion in such a manner as to permit the liquid contents of the bottle to be emptied therefrom although preventing the refilling of the bottle or tampering with the ball valve thereof.

With these and other objects in view, this invention consists of certain novel combinations, constructions and arrangements of parts as will be hereinafter more fully described and claimed.

In the drawings:

Figure 1 is a side elevation of the upper portion of the non-refillable bottle as constructed with this invention.

Fig. 2 is a central vertical section through the non-refillable bottle.

Fig. 3 is a top plan view of the same.

Fig. 4 is a section taken on the line 4—4 of Fig. 2.

Referring to the accompanying drawings by numerals, it will be seen that the bottle body 1 has the neck 2 formed integral therewith. At a junction of the body 1 and the neck 2, however, the structure is reduced as shown at 3 to provide a valve seat 4. After the bottle has been filled with its original liquid contents, the ball 5 is dropped into

the neck 2 so as to normally rest upon the valve seat 4 as shown clearly in Fig. 2.

The hood 6 comprises a substantially cylindrical structure 7 having a closed top 8, although the lower end of the hood is open. An annular rib 9 is formed integral upon the inner portions of the cylindrical structure 7 and before the hood is positioned within the neck 2, this rib 9 is heated to such a degree as to make the same adhere to the interior of the neck 2 when the hood is positioned therein. It is, of course, obvious that the hood 6 as well as the neck 2 is preferably formed of glass and therefore permits the heating of the rib 9 as above referred to. This hood 6 is of sufficient height to permit the ball 5 to be moved from the valve seat 4 when the bottle is inverted as shown in dotted lines in Fig. 2, thus permitting the liquid contents within the bottle body 1 to flow therefrom. When, however, the bottle is in an upright position, the ball 5 will rest upon the valve seat 4 and thus prevent the passage of the liquid into the interior of the bottle body 1.

The glass tubes 10 have inwardly extending lower ends 11 which are carried by the hood 6 and communicate with the interior thereof as shown in Figs. 2 and 4. At the upper ends of the tubes 10 there are also provided inwardly extending portions 12 which terminate in the depending necks 13. As shown clearly in Fig. 2, these necks 13 overhang the top 8 of the hood 6 although they are spaced therefrom for purposes to be hereinafter set forth.

When this non-refillable bottle is in use, the body is filled with liquid as above set forth and therefore, in this action the ball is positioned upon the valve seat. Prior to the placing of the hood 6 within the bottle neck 2, the tubes 10 are secured thereto in the usual manner of connecting glass elements to each other. This is usually done by heating elements while the mass substance is in a heated condition to place the elements in engagement with each other and permitting the same to cool. This action will cause the several elements to be shrunk upon each other and thus be carried in a fixed position. After the tubes have been secured to the hood, the hood is then positioned in the bottle neck and secured therein as above mentioned. When it is desired to

empty the liquid contents from the bottle, the bottle is inverted so as to cause the ball 5 to be removed from the valve seat. The liquid contents will then pass over the seat 4 and will then pass through either one or both of the glass tubes 10 according to the direction in which the bottle is tilted. Passing through these tubes, the liquid will pass also through the inwardly extending ends 10 of the tubes 10 and out through the necks 15 of the tubes so as to be finally dispensed from the outer end of the bottle neck. After the bottle has been emptied, it will be impossible to fill the same for upon turning the bottle to an upright position, the ball 20 will again seat itself upon the valve seat 4, and since the glass tubes 10 are provided, it is obvious that it will be impossible to pass an instrument through these tubes and grip the ball for holding the same from the 25 valve seat while the bottle is being refilled. It is further obvious that as long as the ball is mounted upon the valve seat, it will be impossible to force liquid through the tubes and hood into the bottle.

From the foregoing description, it will be seen that a very efficient non-refillable bottle has been produced wherein the ball valve will prevent the re-filling of the bottle al- 30 though it will permit the original liquid contents to be emptied therefrom. Furthermore, the fitting of the hood over the ball and the extension of the glass tubes over the hood will permit the liquid contents to pass

from the bottle neck but will prevent the 35 unauthorized refilling of the bottle.

What is claimed is:—

A non-refillable bottle of the class de- 40 scribed the combination of a bottle body having a neck formed therein, a valve seat 45 formed within said neck, a ball movably mounted upon said valve seat, a hood positioned within said neck, said hood comprising a cylindrical structure having a closed top, a lower rib formed upon the inner end 45 of said cylindrical structure, said rib fixedly engaging the inner portions of said neck of said bottle, tubes having inwardly extending lower ends, said inwardly extending lower ends fixedly engaging the cylindrical struc- 50 ture of said hood and communicating with the interior of said hood, said tubes having inwardly extending outer portions terminating in the depending necks, said neck over- 55 hanging the closed outer end of said hood and being spaced therefrom whereby when the bottle is inverted the liquid contents may pass through said valve seat, said hood and said tubes first to be dispensed from the bot- 60 tle neck, although when said bottle is in an upright position the ball will seat itself upon said valve, and said hood and tubes will prevent the unauthorized tampering with said bottle thereby preventing the unauthorized refilling of the bottle.

In testimony whereof I hereunto affix my signature.

JESÚS CASUSO.
